UNITED STATES PATENT OFFICE.

JOHN FREDERICK PENDER, OF ST. JOHN, NEW BRUNSWICK, CANADA, ASSIGNOR OF
ONE-HALF TO JAMES PENDER, OF ST. JOHN, CANADA.

WIRE-DRAWING MACHINE.

1,026,119.

Specification of Letters Patent. Patented May 14, 1912.

Application filed July 15, 1910. Serial No. 572,155.

To all whom it may concern:

Be it known that I, JOHN FREDERICK PENDER, of the city of St. John, Province of New Brunswick, Canada, have invented 5 certain new and useful Improvements in Wire-Drawing Machines; and I do hereby declare that the following is a full, clear, and exact description of the same.

My invention relates to wire drawing machines of the type in which the wire is 10 drawn through a die and wound on a revolving drum or wire block.

The object of the invention is to provide 15 improved means for preventing the sudden strain on the wire due to the starting of the block.

With the above object in view my invention may be said to consist of the construction, combination, and particular arrangement of parts hereinafter described 20 and particularly pointed out in the claim. For full comprehension, however, of my invention, reference must be had to the accompanying drawings forming a part of this specification, in which similar reference 25 characters indicate the same parts and wherein—

Figure 1 illustrates in plan view a wire block and die carrier constructed according to my invention; Fig. 2 is a vertical sectional view taken on line A A Fig. 1; Fig. 3 is a detail sectional view of the wire gripping device; and Figs. 4 and 5 are detail perspective views of parts of my improved attachment to the wire block.

In my improved machine the wire block is located in such a position that the die carrier may be normally parallel to and substantially in line with the front of the 40 wire bench or frame *a* on which the wire block is mounted. The wire block comprises a drum or cylinder *b* secured by bolts *b'*, passing through lugs *a'* on the drum, to a disk *a''* and having a hub *b''* and webs 45 *c* formed integrally therewith. The hub *b''* is part of the block and turns on the upper end of an upright shaft *d* which is supported in bearings in the frame *a* and which may be revolved by any suitable means, 50 not shown.

The wire to be drawn is held on a reel, not shown, and is passed through the die box or carrier which will be presently further described, the end of the wire being 55 pointed and inserted in a gripping device

which will also be presently further described and which is fastened to one end of a draw chain *e* the other end of which is attached to a cushioning device provided with a resilient member adapted to contract 60 to prevent a sudden strain on the wire when the block is started. The cushioning device is preferably made in the form of an attachment which can be readily fitted to a wire block already in use and is provided with 65 means to limit the contraction thereof. This cushioning device comprises a longitudinally slideable bolt *g*, guided in a carrier *h* which latter is bored for the purpose and consists of a casting in the form of a 70 wedge having its opposite ends concave and convex respectively and being concentric to the block, one side of the carrier being recessed and the opposite side provided with a hollow boss communicating with and 75 forming part of the boring in the carrier and presenting a bearing face radial to the block to form a bearing for an expansile helical spring *j* which bears therebetween and a cupped washer *k* adjustably retained 80 on the bolt by means of a nut *l* threaded on the latter, the bolt *g* having a hooked end *g'* to which chain *e* is attached. The purpose 85 of the spring *j* is to cushion the shock due to the starting of the block and thereby prevent breaking of the wire, while a sleeve *m* encircling the bolt and encircled in turn by the spring *j* serves to limit the compression of the spring. By arranging the bolt *g*, carrier *h* and related parts as just pointed 90 out a resilient attachment for securing the wire to the wire block is provided which can easily be applied to a block already in use by boring therein the holes for the bolts *i* and *i'*. The block *b* has an opening *n* to 95 accommodate the chain *e*, and to prevent the latter from swinging inwardly and striking against the edge *n'* of this opening when the block starts revolving a sheave *o* is provided against which the chain bears, 100 such sheave being mounted on a plate *o'* located in a recess *p* in one of the webs *c* and secured to the web by bolts or screws *o''* the web being recessed to accommodate 105 the plate and sheave.

The gripping device before mentioned to which chain *e* is secured comprises a gripping plate *r* having an eye *s* formed thereon to serve as a means of attachment for the chain. A pair of converging sockets 110

or borings *t* are formed in the gripper plate and contain and guide in their adjacent ends gripping jaws *v* having adjacent serrated faces *w* between which the wire, which is shown at *x*, is gripped. A hole *l*' through the plate *r* allows the wire to be passed therethrough a sufficient distance beyond the gripper jaws to insure a firm bite on the wire. To prevent the jaws turning in their sockets and thereby losing their grip on the wire when the latter is being drawn onto the block a pair of pins *2* screwed into the outer walls of the borings *t*, project into grooves *3* formed in the jaws *v*, any turning movement of the jaws being thereby prevented while the grooves permit of movement of the jaws necessary to compensate for wear and permit the jaws being separated when it is desired to insert the wire or withdraw it. To cause the gripping device and draw chain to keep out of the path of the wire as it is being wound around the block a chain *5* is connected to the draw chain at a point adjacent to the gripping device and is attached to a small drum *6* containing a clock spring *7* by means of which tension is kept on the chain *5*, such drum being rotatably mounted on a bracket *8* secured to the block.

The wire drawing die *20* is carried in a die box or carrier consisting of a casting *25* having a transverse opening *26* therethrough near its forward end to constitute the box receiving the die, which latter is clamped in place by a clamping screw *27* projecting downwardly through the top of the box and bearing on the top of the die. As it has been found that the pull of the wire on the die when the block is started has a tendency to displace the die in its box and throw the matrix out of alinement with the wire, a horizontal adjusting screw *28* is screwed through a tapped boring in the front of the box *25* and bears against the die at a point near its outer end which is the end farthest from the wire block; the screw being located in that position in order that the position of the die with relation to the wire may be regulated and binding of the wire in the die prevented. By turning the screw in one direction the die can be adjusted inwardly while by turning it in the opposite direction the die is released and the tension of the wire is permitted to pull it outwardly.

The die box or carrier *25* is pivoted at a point near its rear end as at *25*^a on a pair of lugs *30* formed on a base plate *31*, between which lugs the rear end of the die box is located. The rear portion of the carrier is preferably, as shown in Fig. 1, narrower than the front or die holding portion so as to bring the pivoted end and lugs *30* within the compass of the front portion of the box, the base plate throughout being of substantially the same width as the front part of

the carrier. Bosses *32* are provided on the sides of the carrier to serve as hubs therebetween and the lugs *30*.

The base plate *31* is mounted on the bench or frame *a*, on which the wire block is also mounted, being preferably located at the front edge of the bench and to one side of the wire block. The base plate is pivoted on the bench *a* to swing horizontally thereon, and this pivotal connection is effected by means of a bolt *36* passing vertically through the rear end of the base plate and the bench *a*; the portion of the bolt passing through the base plate being enlarged and forming a shoulder which rests upon the bench, a nut *39* threaded on the lower end of the bolt serving to secure it to the bench.

To provide an effective abutment behind the pivot point of the carrier *25* to withstand the force exerted upon the die by the pull of the wire being wound on the drawing block, the carrier extends, as shown particularly in Fig. 2, a considerable distance to the rear of the pivot point, while to allow the front end of the carrier to swing upwardly without any chance of the extended rear portion striking the base plate the pivot point is placed a sufficient distance from the base plate to have the bottom of the carrier spaced therefrom. The forward end of the carrier *25* rests, when the machine is not running, upon the base plate and to cause it to assume a horizontal position a support in the form of a transverse rib *39* is preferably provided and may be located as shown on the forward top portion of the base plate. As it is undesirable to have the weight of the front portion of the carrier and the die cause the latter to bear down upon the wire being drawn, a spring *40* is connected at one end as at *41* to the top of the carrier near the front end of the latter, the other end of the spring being connected to a hook *42* on a bar *43* set between shoulders *44* and *45* formed on the side of an extension *46* cast in line with the inner one of the lugs *30*. The spring *40* supplements the pivots *25*^a and *36* in keeping the die and carrier in alinement with the draft of wire by holding the carrier up when the wire is winding up the block.

To provide a receptacle for containing soap, oil or other lubricant for the wire a chamber *50* is formed in the carrier to the rear of the opening *26*, a passage *51* for the wire leading from this chamber to the opening *26* and thence to the front of the carrier.

Operation: The end of the wire to be drawn is first secured in the gripping device. The machine is then started and as the block *b* starts to revolve and tension is put on the wire the spring *j* is compressed and yields enough to take the sudden strain off the wire as it is being started, the sleeve *m* being arranged to stop the yielding move-

ment when the wire has been started to prevent the spring being compressed far enough to be broken and also to obviate the risk of a recoil of the spring injuring the wire. 5 The drawing of the wire then proceeds in the usual manner, the tension of the clock spring 7, acting through drum 6 and chain 5, keeping the gripping device and draw chain out of the path of the wire, and should 10 the die 20 at any time get out of alinement with the wire this can be readily remedied by adjusting screw 28.

What I claim is as follows:—

A wire drawing attachment for a hollow cylindrical wire drawing block having 15 a hub and an outer wall and including a bracket extending between and abutting against the hub and the outer wall of the

block, bolted to the wire block and having a boss thereon and a hole therethrough and 20 through the boss, a longitudinally slideable bolt within the hole, one end of such bolt being hooked and adapted to have a chain connected thereto, a sleeve upon the bolt, of less length than the latter and abutting 25 against the boss, a spring encircling the bolt and sleeve and bearing against the boss, a washer upon the bolt and a nut for securing such washer in place.

In testimony whereof, I have signed my 30 name to this specification, in the presence of two subscribing witnesses.

JOHN FREDERICK PENDER.
